UNITED STATES PATENT OFFICE.

GUIDO PO, OF ROME, ITALY.

ARRANGEMENT OF SHIP-RUDDERS.

1,247,448.

Specification of Letters Patent. Patented Nov. 20, 1917.

Application filed August 10, 1915. Serial No. 44,823.

To all whom it may concern:

Be it known that I, Guido Po, a subject of the King of Italy, resident at Rome, in the Kingdom of Italy, have invented certain new and useful Improvements in the Arrangement of Ship-Rudders, of which the following is a specification, reference being had therein to the accompanying drawings.

10 The present invention refers to certain improvements in the arrangement of rudders of ships the object of which is to better the latter's evolutional qualities, to brake same and to reduce head-way when stopping and to lessen the danger ensuing from rudder damages in navigation. By these improvements, dangers of collision or stranding may, in the majority of cases, be avoided or at least diminished.

20 To properly understand the following description, reference must be had to the annexed drawings, in which Figure 1 shows the evolution curves of a ship steered by the means it at present has at disposal when 25 maneuvering with the view of avoiding an obstacle.

Fig. 2 is the side elevation of a ship provided with two rudders placed both in the middle plan.

30 Fig. 3 is a plan of the same ship.

Fig. 4 shows how without varying the usual arrangement of the stern rudder, a second rudder, according to the present invention, can be added to a merchant ship.

35 The great maritime disasters of these last few years have led to the adoption of various life saving provisions on board ships. Among the more important and recent provisions made compulsory by the regulations 40 in force with vessels of all marines may be enumerated the following: collision bulk-head with sliding doors controlled from the upper decks; radiotelegraphy plant suited to the type of ship; provision of an adequate number of life boats for the whole 45 of the crew and the passengers.

All these provisions, however, come into operation only after the collision or stranding, and consequently are only designed to 50 mitigate the latter's effects. None of any such provisions—with the exception perhaps of the radiotelegraphy—aims at avoiding or diminishing the possibility of similar disasters.

55 It is accordingly very desirable to provide means for preventing disasters of the

above nature, and such means might consist in the adoption of steering and controlling apparatus of such nature as to better not only the evolutional qualities of the 60 ship but also to coöperate in braking same and reducing headway on the sudden appearance of danger ahead, as well as to render the consequences of rudder damages less dangerous during navigation.

65

The purpose of the arrangements forming the object of the present invention is to improve the efficiency of steering means mainly for the objects above alluded to.

For instance, in the case of merchant vessels:

These have almost all one single stern rudder of limited dimensions and are provided with a single steering gear. It thus follows that their evolutional qualities are 75 deficient, and further that any damage incurred to their sole rudder, or to its steering-gear may, in certain conditions of weather or in certain latitudes, mean arising of serious danger for the ship itself.

80

Coming now to the effects of the rudder's maneuver in the case of imminence of stranding or collision, let a ship —a— (Fig. 1) be navigating at a given velocity in the direction —ab—. The vessel suddenly discovers a peril —e— at a certain distance on its course. The peril may be from some obstacle, or a ship unexpectedly sighted on the course, or any other danger whatsoever.

85

Whatever the peril —e—, hidden to the 90 last moments by fog, heavy rain, darkness, or other reasons, there being immediate danger of collision, and whatever the course of —a— with respect to —e—, the ship —a— will seek in every possible way to 95 avoid the catastrophe, and according to the space available will try to execute one of the following maneuvers:

(1)—To advance with the helm all on one side or the other without changing the 100 screw's sense of rotation at all.

(2)—To immediately reverse the screw motion so as to stop the vessel within the shortest possible distance either (a) by maintaining the same course or (b) by 105 turning on either side, with the helm all to port or starboard.

In the first case, to which refers the lines —ac—, —ac'— of Fig. 1, the maneuver will be convenient when sufficient room for turning is allowed by hydrographic conditions; so that after an evolution of 90° the curve

110

$—ac'$ of the stern positions ($—ac$ being the curve of the head) may pass clear from the obstacle $—e$.

In the second case, (a) the maneuver will be convenient if the straight course forward made by the ship $—a$, during the reversal of the screw's movement for cutting off the head way is shorter than the distance $—ac$, or that lesser distance to which it would be reduced during the maneuver if $—e$ were a ship advancing toward $—a$, while the maneuver in the second case (b) represented in the figure by the lines $—ad'$ — $—ad$, the respective curves of stern and head will be the one generally preferred, because while making sure of the minimum advance onward, it admits a lateral displacement on the side most convenient.

In order to be able to accomplish successfully the above maneuver, ships in general, and more particularly merchant ships, must have attained the highest perfection in steering and controlling means, which at present is very doubtful.

In fact, on considering any modern transatlantic, it will be seen that the same has generally a single rudder, the dimensions of which are very small with respect to what they might and should be. The normal proportion between the area of the rudder and the area of the middle line plane, runs to about 1:50, or 1:60; while, there are ships of war, in which the finest evolutional qualities are demanded for tactical reasons, where the said proportion rises to 1:30.

This means it is desirable for merchant ships, especially passenger boats, to greatly increase the size of their rudders.

Again, on further examination of modern commercial ships it will be seen that the introduction of two or four turbine screws has led up to a greater difficulty in cutting off the forward movement in stopping, through the turbine's insufficient power to act with reversed screws.

Summing up, the evolution deficiency in modern commercial ships ensues chiefly from an insufficient area of rudder, and from the difficulty of cutting off the forward movement when stopping.

The following arrangements provide against these two inconveniences:

(1)—Ships are furnished, especially those for passenger transport, with two rudders (Figs. 2 and 3) placed on the same middle longitudinal plane, one $—s^1$ abaft of the other $—s$, the aggregate area of which would be about one thirtieth of the middle line transverse plane of the ship.

With the adoption of the two rudders in the longitudinal middle plane, the ship's stern must be a little more sharp than at present, which will give better evolutional qualities.

This steering area is subdivided between

the two rudders placed along the ship's longitudinal middle plane as indicated in the Figs. 2 and 3, so that the area of the forward rudder may be about $\frac{1}{5}$ th larger than that of the stern rudder.

The two rudders must be situated at a proper distance from each other so as not to lessen their respective effects; the space from one to the other should be about one-eighth or one-tenth of the ship's length. This distance between the two rudders was found to be the more convenient in respect to the proportions usually adopted in the constructions of ships of various sizes. The action of the rudders is two fold: namely: when they are bodily put over on the same side, they will work together to change the ship's course, while when they are turned over in opposite directions, their action serves only to reduce the forward motion of the ship without changing its course. In order to obtain an efficacious action, the rudders should not be situated too near the center of the ship so as not to unduly reduce their turning effect. At the same time, as explained before, the two rudders must be situated at a sufficient distance one from the other so as not to influence each other. From the studies confirmed by various experiments made in this respect it resulted that the afore cited conditions are met in the best possible way by fixing as interval between the two rudders a distance from $\frac{1}{8}$ to $\frac{1}{10}$ of the ship's length.

When the rudders are put over in opposite directions, it is necessary that the course of the ship be kept unchanged. Therefore it is necessary that the moments of rotation developed by the two rudders be equal and of opposite direction and as the lever arm of the stern rudder is longer than the lever-arm of the bow-rudder, it is necessary that the area of the rudders be in inverse ratio of the said arms. As already stated this is obtained by giving the bow-rudder an area of $\frac{1}{5}$ larger than that of the stern rudder.

(3)—These rudders are provided (Figs. 2, 3, and 4) with steering gear $—g$ with independent transmissions $—h$ right to commander's bridge $—f$ whereby means of suitable controlling devices they can be easily worked either separately or both together.

From the same commander's bridge a transmission $—i$ allows the control of the gear $—k$ for reversing the movement.

(4)—The rudders are arranged so that they can be put all on one side simultaneously in the same direction or in opposition; the helm angle for both longitudinal rudders instead of being limited, as it commonly is at present, to 30° or 35° , may be run up to 90° on the two sides (Figs. 2, 3, and 4).

(5)—A half balanced form is given to the rudders so as to diminish the power neces-

sary for putting them aside (adopting on a broad line the arrangements indicated by Figs. 2 and 4).

A ship furnished with the aforesaid apparatus, on suddenly having to avoid a peril ahead, will have a greater chance of escape in executing one of the following maneuvers:—

(1)—Reversing the screw's movement and 10 at the same time putting both rudders hard over at an angle of 90° in opposite directions, so as to add to the resistance opposed by the screw's reverse motion that constituted by the total area of the rudders.

(2)—Putting both rudders at about 30° or 35° in the same direction on the side proper for getting the maximum turning effect, and for reducing to a minimum the forward motion of the vessel after 90° of 20 evolution.

(3)—Putting the two rudders at an angle of about 30° or 35° on the same side and at the same time reversing the screw's movement till the ship stops.

All these measures will have as a result the reduction of the circle in which the ship turns other conditions being equal, to about half the present, and the notable diminution of the course for shutting off the movement. 25 These improved maneuvering qualities will, in many cases, coöperate to prevent the repetition of terrible maritime disasters.

Copies of this patent may be obtained for five cents each, by addressing the "Commissioner of Patents, Washington, D. C."

It is observed above, that the screws as well as rudders may be controlled by means of suitable apparatus from the commander's bridge. The same does not exclude the screws as well as rudders being—as in fact they are—generally controlled also from other parts of the vessel, and especially from the pilot's station. 35

Claims:

1. A ship provided with two rudders placed one behind the other in the middle longitudinal plane, the area of and the distance between the rudders being such as 45 to develop equal and opposite turning moments when set over by equal angles in opposite directions.

2. A ship provided with two rudders arranged at the longitudinal center thereof, 50 one in front of the other, the rudders being of half balanced form and the forward one having a greater area than the rear one, and mechanism for operating the rudders, whereby they may be operated simultaneously or 55 separately and swung into the same or opposite directions.

In testimony whereof I affix my signature in presence of two witnesses.

GUIDO PO.
